UNITED STATES PATENT OFFICE.

FRANCESCO FRAZZI, OF CREMONA, ITALY.

EARTHQUAKE-PROOF AND OTHER STRUCTURE.

Specification of Letters Patent.

Patented Apr. 11, 1916.

1,178,911.

Application filed June 8, 1910. Serial No. 565,823.

To all whom it may concern:

Be it known that I, FRANCESCO FRAZZI, a subject of the King of Italy, residing at Cremona, in the Kingdom of Italy, have invented certain new and useful Improvements in Earthquake-Proof and Other Structures, of which the following is a specification.

This invention relates to building constructions and has for one of its objects to provide a structure which is highly elastic and capable of resisting seismic shocks and lateral stresses. This is accomplished by employing building blocks of the special shape hereinafter described, and by reinforcing the same with metallic wires or the like and concrete or cement applied in the manner hereinafter indicated.

The invention is illustrated in the accompanying drawings, in which—

Figure 1 is a vertical section of a portion of a wall constructed in accordance with the invention; Fig. 2 is a vertical section of a portion of a wall and floor beam showing a different manner of positioning the building blocks; Fig. 3 is a perspective view illustrating the manner in which the horizontal reinforcing wires may be connected to the vertical reinforcing wires; Fig. 4 is a perspective detail view illustrating the manner in which the horizontal reinforcing wires may be connected to the frames of doors, windows and the like; and Fig. 5 is a perspective view illustrating the manner in which the horizontal reinforcing wires may be secured to the vertical reinforcing wires of the reinforced cement posts or columns.

Referring to the drawings, it will be noted that the building blocks are denoted by the reference character 1. They may be made of any suitable material, such as cement, clay and the like, and are provided on two of their adjacent faces with dovetail grooves 2 and on their other two faces with dovetail ribs or projections 3. In Fig. 1 each of the blocks is provided on each face with only one groove or one projection, but it is obvious that a greater number of such grooves and projections may be used as shown on the larger blocks 1' of Fig. 2. The type of wall construction shown in Fig. 1 may be used for party walls or interior partitions, while that shown in Fig. 2 may be used for perimetral walls of greater thickness. It may, therefore, be desirable

in the type of wall shown in Fig. 2 to use a number of the larger size blocks 1'. The general principles of construction in Figs. 1 and 2, however, are the same as will hereinafter appear.

In Fig. 1, the blocks are disposed horizontally and superposed so that the dovetail projection on the upper surface of one block will engage in the dovetail groove in the lower surface of the superposed block. In the grooves at the sides of the blocks are positioned horizontal reinforcing elements, such as the wires "t". These may be connected to the supporting members of the building, and, if desired, may also be connected to the vertical reinforcing wires, and door and window-frames. In Fig. 5, the horizontal wires *t* are shown connected to the vertical wires *t'* of the reinforced column or post *a*. Fig. 3 shows the manner in which these horizontal wires "t" may be connected to the vertical reinforcing wires *t'*, and Fig. 4 shows the manner in which they may be connected to the frames *b* of doors, windows, and the like. The vertical reinforcing wires just mentioned are shown in Figs. 1 and 2 and may constitute the reinforce for an external coating of concrete or cement, indicated at *E*. The dovetail projections on the blocks serve to anchor this coating of concrete, as clearly indicated in the drawings. A coating of cement or concrete is also applied to that surface of the wall provided with the grooves and serves to anchor the wires *t* in the grooves and also to produce continuous ribs which pass through all the aligned grooves of the blocks of each course, thereby aiding in locking the blocks in place.

It is obvious that the blocks may be positioned in any suitable manner, as indicated in Fig. 2, in which the blocks 1 are vertically disposed. Furthermore, the type of wall illustrated in Fig. 2 is of greater thickness than that of Fig. 1, as in Fig. 2, the blocks are not superposed in a single vertical series, as in Fig. 1. However, it will be noted that even in Fig. 2, the special shape of the blocks permits a wall to be constructed in which the blocks of the several courses are interlocked by the engagement between the coöperating grooves and projections, and which will present at one side dovetail grooves for the reception of reinforcing wires and cement or concrete, and at the other side dovetail projections

capable of anchoring a coating of concrete. In both Figs. 1 and 2, the grooves 2 run in a horizontal direction, but it is obvious that by standing the blocks on end, they may be made to run in a vertical direction to receive the vertical reinforcing wires.

Fig. 2 in addition to showing a portion of a wall, also shows a portion of a floor beam U constructed in accordance with the invention and involving the use of the interlocked blocks presenting their projections 3 to the concrete flooring U' and their grooves 2 to the ceiling E'. It will now be seen that the blocks may be positioned in various ways and may be of various shapes and still be capable of forming a wall or other portion of a building in which the blocks are interlocked to each other and in which grooves will occur in one surface 20 of the wall for the purpose of receiving reinforcing wires which, in turn, may be connected to the supporting elements of a building, and further in which projections will occur on the other surface of the wall 25 capable of anchoring a body of concrete. As the blocks are themselves interlocked and elastically reinforced against lateral stresses by the reinforcing wires which are connected to the supporting members of the 30 building, and furthermore, as the rein-

forcing wires are anchored directly in the grooves of the blocks by the cement or concrete coating, it is obvious that a structure of great strength and elasticity is produced.

What I claim is:—

In a construction such as described, the combination with the supporting elements of a building, of a plurality of blocks or slabs arranged in courses, said blocks or slabs provided with coöperating dovetail 40 projections and recesses whereby the blocks of one course are interlocked with those of another course, said blocks provided on their outer vertical faces with dovetail grooves, reinforcing wires or rods positioned 45 in said grooves and connected to said supporting elements to strengthen the construction against lateral stresses, cement or concrete applied to said blocks and serving to lock said rods in the grooves, and dove- 50 tail projections on the outer faces of certain of said blocks adapted to be anchored in cement or concrete.

In testimony whereof I affix my signature in presence of two witnesses.

FRANCESCO FRAZZI.
